UNITED STATES PATENT OFFICE.

CHARLES E. SNEIDER, OF BALTIMORE, MARYLAND, ASSIGNOR OF ONE-HALF
TO MARTIN GILLET GILL, OF SAME PLACE.

BREECH-LOADING MAGAZINE FIRE-ARM.

SPECIFICATION forming part of Letters Patent No. 417,595, dated December 17, 1889.

Application filed August 31, 1889. Serial No. 322,509. (No model.)

To all whom it may concern:

Be it known that I, CHARLES EDWARD SNEIDER, a citizen of the United States, residing at Baltimore, Maryland, have invented 5 new and useful Improvements in Breech-Loading Magazine Fire-Arms, of which the following is a specification.

This invention relates to my breech-loading fire-arm, which is provided with a cartridge-magazine in the form of a slotted tube movably secured along and parallel to the gun-barrel, and from which the cartridges pass to the breech-frame, where they are acted upon by a cartridge inserter-ejector operated 10 by cocking the hammer to insert the cartridges laterally into the breech-frame to load the gun, and at the same time eject the empty shells, all as in my applications for Letters Patent filed August 24, 1889, Cases A and B, 15 Serial Nos. 321,880 and 321,881.

The objects of my present invention are to provide the fire-arm with a cartridge-magazine that axially turns or rotates to expose the slot through which the interior is inspected, to 20 provide the magazine with novel means for holding the cartridges therein when the barrel carrying the magazine is detached from the breech-frame, to provide novel means for conveniently unloading or removing cartridges from the magazine by a simple backward movement thereof on the barrel when the latter is detached from the breech-frame, and to otherwise improve the prior construction and operation of cartridge-magazines. 25 To accomplish all these objects, my invention involves the features of construction, arrangement or combination of devices, and principles of operation hereinafter described and claimed, reference being made to the accompanying drawings, in which—

Figure 1 is a right-hand side elevation of a repeating-rifle embodying my invention. Fig. 2 is a detail perspective view of the cartridge-magazine, looking at its slotted side. Fig. 3 30 is a detail transverse sectional view taken on the line $x-x$, Fig. 1. Fig. 4 is a similar view taken on the line $y-y$, Fig. 1; and Fig. 5 is a like view showing the magazine turned or rotated to expose its longitudinal sight-slot.

50 In order to enable those skilled in the art to make and use my invention, I will now de-

scribe the same in detail, referring to the drawings, wherein—

The numeral 1 indicates the stock; 2 the breech-frame, and 3 the detachable gun-barrel, of a repeating fire-arm wherein the breech-frame is provided with a locking device to detachably secure the barrel, and with a lateral enlargement 4, containing the cartridge inserter-ejector 5, which is operated by the 55 cocking of the hammer to insert a fresh cartridge and eject an empty shell, all as in my applications hereinbefore alluded to, or of other constructions suitable for the conditions required.

The gun-barrel is provided at one side with a front and a rear circular loop or guide bearing 6, in which is arranged to axially turn or rotate a tubular cartridge-magazine 7, having a longitudinal slot 8 along its side adjacent 60 to the barrel, and open at its rear end for automatically delivering the cartridges to the inserter-ejector 5, this being effected by a coiled spring 9, located within the magazine and acting on the plunger or follower 10 to 65 constantly press it toward the breech-frame.

The magazine, in addition to axially turning or rotating, is adapted to slide lengthwise in a line parallel with the barrel for the purpose of adjusting the magazine to the position 70 indicated by dotted lines, Fig. 1, whereby a space is provided between the lateral enlargement 4 and the rear open end of the magazine for the introduction into the latter of the cartridges to be fired. The rear end of 75 the magazine is provided with a longitudinally-arranged leaf-spring 12, secured at its front end to a part of the magazine and free at its rear end, where it is furnished with a dog or hook 13 to engage and release the rear 80 cartridge, as hereinafter explained. To slide and turn the magazine, I provide it with a suitable finger-piece, which, as here exhibited, is composed of a rigidly-attached milled head 14, partially encircling the magazine and of 85 such construction as to permit it to be manipulated for sliding and turning the magazine.

It is frequently desirable to detach the barrel from the breech-frame for such purposes 90 as repairs, cleaning, and unloading the magazine, and while detaching the barrel it is re-

quired to retain the cartridges in the magazine at least until such time as the sportsman is prepared to unload or discharge the contents. To accomplish this with ease and facility, I provide the magazine with novel means whereby the cartridges are dogged and held when the magazine is slid forward on the barrel, and the dogging action is relieved and the cartridges released to follow the impulse of the coiled spring when the magazine is slid backward on the barrel. The means here shown for effecting this purpose consist of the leaf-spring 12, with its dog or hook 13, and the rear collar or guide bearing 6 on the barrel, the arrangement being such that the leaf-spring moves lengthwise with the magazine between the latter and the interior surface of such collar or guide bearing. The action of the leaf-spring is such that when not under restraint its hooked end springs away from the axis of the magazine, as in Fig. 2, and permits the free passage of the cartridges; but if the magazine be slid forward on the barrel the rear collar or guide bearing presses the hooked end of the leaf-spring toward the axis of the magazine, and the cartridges are thereby dogged and held therein. The barrel can now be disconnected from the breech-frame, and then by sliding the magazine backward the leaf-spring is relieved from restraint and its hooked end springs away from its dogging position, whereupon the cartridges will be pushed out into the hand of the sportsman or into any other receptacle. In a similar manner, if the barrel with its magazine be in position on the breech-frame, as in full lines, Fig. 1, the leaf-spring is out of its dogging position, and the cartridges will at the proper time be automatically pushed into position to be operated for loading the gun; but if the magazine be slid forward into the position indicated by dotted lines, Fig. 1, the rear collar or guide bearing will press the leaf-spring into its dogging position to retain the cartridges in the magazine. In the position last mentioned the magazine can be conveniently loaded or charged with the ammunition. The breech-frame is preferably provided with a portion, as at 15, Fig. 1, to conceal the leaf-spring or dog when the magazine is slid rearward against the lateral enlargement 4. This portion 15 may form a rest for the cartridges being inserted into the magazine when the latter is slid forward to the position indicated by dotted lines; but as this feature is not indispensable, I do not deem it essential to further illustrate the same.

The magazine is preferably held against

axial rotation when slid back, as in full lines, 60 Fig. 1, and this may be effected by any suitable means. For example, when the magazine is pushed back on the breech-frame, the leaf-spring will move away from the axis of said magazine and bear against the side of 65 the breech-frame, which will render it impossible to turn the magazine except when it is slid forward; but this is not essential, for the magazine may or may not be adapted to turn when pushed back on the breech-frame. 70

The side of the gun-barrel serves to cover and conceal the slot in the magazine when the latter is in its normal position, as in Fig. 4; but by axially turning the magazine its slotted side is brought uppermost and exposed, as in Fig. 5, in which position the sportsman can at a glance inspect the interior of the magazine and instantly see the number of cartridges therein contained. I prefer to extend the sight-slot the full length of the 80 magazine, or substantially so, but do not confine myself thereto; and, further, as regards the axial rotation of the magazine to expose and conceal the sight-slot, I do not limit myself to a lengthwise-sliding magazine, though 85 the latter is the superior form of the invention.

Having thus described my invention, what I claim is—

1. The combination, with a repeating fire-arm, of a slotted axially-rotating magazine mounted in bearings on the barrel, substantially as described. 90

2. The combination, with a repeating fire-arm, of an axially-rotating magazine having 95 a sight-slot which is concealed when the magazine is in its normal position and is exposed when said magazine is axially rotated from its normal position, substantially as described. 100

3. The combination, with a repeating fire-arm, of an axially-rotating magazine mounted in bearings on the barrel and having a sight-slot which is concealed by the barrel when the magazine is in its normal position and is 105 exposed when the said magazine is axially rotated from its normal position, substantially as described.

4. The combination, with a fire-arm, of an axially-rotating and lengthwise-sliding magazine having a longitudinal sight-slot in one side, substantially as described. 110

In testimony whereof I have affixed my signature in presence of two witnesses.

CHARLES E. SNEIDER.
